[57] CLAIM

The ornamental design for a corner support bracket for
plaques or the like, as shown and described.

DESCRIPTION

FIG. 1 is a front perspective view of a corner support
bracket for plaques or the like showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view thereof, the fragmented
frame shown in broken lines for illustrative purposes
only.
